UNITED STATES PATENT OFFICE

120,530

DESIGN FOR A CHECK IMPRINTING MACHINE OR SIMILAR ARTICLE

Gilbert L. Pierce, Rochester, N. Y., assignor to
The Todd Company, Inc., Rochester, N. Y., a
corporation of New York

Application July 3, 1939, Serial No. 85,822

Term of patent 14 years

To all whom it may concern:

Be it known that I, Gilbert L. Pierce, a citizen of the United States and a resident of Rochester, in the county of Monroe and State of New York, have invented a new, original, and ornamental Design for a Check Imprinting Machine or Similar Article of which the following is a specification, reference being had to the accompanying drawings, forming a part thereof.

Fig. 1 of the drawings is a perspective view of a check imprinting machine or similar article, embodying my design.

Fig. 2 is a similar view of the same, looking at it obliquely from the opposite side.

Fig. 3 is a plan view of the machine, and

Fig. 4 is a rear elevational view of the machine. The essential features of my design are shown by full lines in the drawings.

I claim:

The ornamental design for a check imprinting machine or similar article, substantially as shown and described.

GILBERT L. PIERCE.
